R. E. ESTES & J. P. INMAN.

SPARK PLUG.

APPLICATION FILED DEC. 22, 1909.

965,380.

Patented July 26, 1910.

UNITED STATES PATENT OFFICE.

ROBERT E. ESTES AND JOHN P. INMAN, OF MIDLAND, TEXAS.

SPARK-PLUG.

965,380.

Specification of Letters Patent. Patented July 26, 1910.

Application filed December 22, 1909. Serial No. 534,537.

To all whom it may concern:

Be it known that we, ROBERT E. ESTES and JOHN P. INMAN, citizens of the United States, residing at Midland, in the county of 5 Midland and State of Texas, have invented certain new and useful Improvements in Spark-Plugs, of which the following is a specification.

Our invention relates to improvements in 10 spark plugs such as are used in explosive engines, and the objects of the invention are to provide means whereby the electrodes of the spark plug may be readily cleaned and whereby they may be adjusted into greater 15 or less contiguity with each other.

For a full understanding of the invention and the merits thereof, and to acquire a knowledge of the details of construction, reference is to be had to the following 20 description and accompanying drawing, in which:

Figure 1 is a longitudinal diametrical section through one form of our improved spark plug; Fig. 2 is a like view, showing another 25 form of our improvement; and, Fig. 3 is a perspective view of the inner end of the spark plug.

Corresponding and like parts are referred to in the following description and indicated in all the views of the drawing by the same reference characters.

Two forms of our invention are shown, one of which is illustrated in Fig. 1, and the other in Fig. 2.

35 Referring to Fig. 1, 2 designates a socket or shell to which is attached the electrode 3, preferably formed of two wires crossed at right angles to each other. This socket or shell we shall hereafter term the plug base.

40 This plug base is provided with the reduced screw-threaded portion 2^a whereby it may be attached to the casing of an engine. 4 designates a core of porcelain or other insulating material of usual construction

45 which is provided with the metallic bushing 5, the porcelain core being formed with a shoulder 6 above and below the bushing so that the bushing is held in rigid relation with the porcelain core. The lower end of

50 the porcelain core is spaced from the inside face of the plug base 2, and the porcelain core is provided with a central internal passage 7 which is enlarged at its lower portion. Carried within the internal passage 7 is the metallic sleeve 8 which is shoul-

dered at its lower end to fit the enlarged

portion of the bore 7. This sleeve 8 is screw-threaded at its upper and lower ends for engagement with screw threads upon a central electrode pin 9. This pin 9 extends 60 longitudinally through the core 4 and projects slightly below the same into proper contiguity with the electrode 3. The upper end of this pin is bent at right angles, as at 10, and is provided with the knob 11 of non-conducting material whereby the pin may be rotated. It will be obvious that when the pin is rotated in one direction or the other, it will be moved either up or down within the core so that it may be brought either 70 into frictional engagement with the contact 3^a on the electrode 3, or out of contact therewith and separated therefrom to any extent desired. Engaging with the upper end of the sleeve 8 is the nut 12 which bears upon 75 the upper end of the porcelain core or insulator 4. Packing is interposed between this nut and the upper end of the core. Surrounding the upper end of the pin 9 is the usual binding nut 13 whereby the spark 80 plug may be connected to the batteries or magneto. A lock nut 12^a is provided which engages the screw rod 9, so as to hold the screw rod in its set position.

It will be seen that the bushing 5 has 85 screw-threaded engagement with the plug base 2 so that the bushing 5, and with it the core 4, may be adjusted inwardly or outwardly within the plug base. In order to hold the bushing and core in their adjusted 90 positions, we provide the lock nut 14 which surrounds and engages with the screw-threaded exterior of the bushing 5 and bears upon the upper end of the plug base. It will be seen that this construction provides, 95 as before stated, for the adjustment of the bushing, the core and the electrode pin into greater or less contiguity with the electrode 3, and that when once adjusted, the bushing may be locked in position by means of the 100 lock nut 14 and be held rigidly in this adjusted position. In addition, by rotating the electrode pin, the pin itself may be brought into greater or less contiguity with the contact 3^a so to have either frictional engagement 105 therewith whereby soot upon the electrodes may be rubbed away and the contact points kept bright, or else whereby the electrode 3 may be properly adjusted in relation to the electrode 3 to secure the proper spark for 110 different circumstances of operation.

In Fig. 2, we show another and simpler

form of our invention, and in this figure 2 designates the plug base, 2^a the exteriorly threaded neck thereon, 3 the fixed electrode, 4 the porcelain core, 5 the bushing, and 14 the lock nut whereby the bushing is held in its adjusted position upon the plug base. Passing centrally through the core is the electrode pin 15 which, in this case, is formed so as to have rigid engagement with 10 the core 4, and is not separately adjustable to the core. This pin is shouldered, as at 16, at its lower end so as to hold it in its rigid engagement, and the pin extends out through the enlarged passage, through the 15 lower end of the core, and projects slightly beyond the core in more or less contiguity with the contact 3^a on the electrode 3. The upper end of the pin 15 is screw-threaded, as at 17, for engagement with the binding 20 nut 18 whereby the wire from the battery or magneto may be attached to the plug. In this form of the device, as before stated, there is no separate adjustment of the electrode pin 15, but by releasing the lock nut 25 14, the bushing 5 may be rotated to move the core 4 and the contact pin toward or from the electrode 3. Thus, the electrode pin may be brought into greater or less contiguity with the contact point 3^a, or the end 30 of the electrode pin may be brought so as to have a rotating contact with the contact 3^a so that the same may be cleaned of soot and kept in a bright condition.

It will be seen that our device provides 35 for an easy and accurate adjustment of the two contact points toward or from each other, and further, provides for a locking of these points in their adjusted position, and that it also provides for cleaning these 40 points without the necessity of entirely withdrawing the plug from its engagement with the engine. The invention is simple, can be cheaply made, and is entirely effective in practice.

45 Having thus described the invention, what is claimed as new is:—

1. A spark plug including a plug base, an insulating core, an electrode pin extending entirely through the core and projecting beyond 50 its inner end, separate and independent means for adjusting the core with relation to the plug base and for adjusting the electrode pin longitudinally through the core, and means for holding the core and pin 55 locked in their adjusted positions.

2. A spark plug comprising an outer plug base screw-threaded on its interior, a screw-threaded bushing, a lock nut in the outer end of the plug base and having engagement therewith, an insulating core supported within said bushing, an electrode pin extending entirely through the core and projecting beyond its inner end, and means for connecting the pin to a conducting wire.

65 3. In a spark plug, an outer plug base

screw-threaded on its interior, a bushing screw-threaded on its exterior and engaging with the plug base, a lock nut surrounding the bushing, a core of nonconducting material rigidly supported in the bushing, an electrode pin extending through the core, and means on said electrode pin for engaging a conducting wire. 70

4. A spark plug comprising a plug base, screw-threaded on its interior and having 75 an electrode carried upon its inner end, a bushing having screw-threaded engagement with said base, a core of insulating material rigidly mounted with the bushing and having a passage extending longitudinally 80 through its center, a rotatable electrode pin in said passage, the lower end of the pin projecting below said core, the upper end of the pin being formed with screw threads, a binding nut engaging said screw threads, 85 and a locking nut holding the pin in any desired adjusted position.

5. A spark plug comprising a plug base having a screw-threaded neck, an electrode attached to said neck and projecting beneath 90 the base and having a contact point, an exteriorly screw-threaded bushing engaging with the outer end of the base, a lock nut on said bushing, a core of insulating material supported within the bushing and having 95 a longitudinal passage extending through its center, the passage at its inner end being enlarged, a screw-threaded electrode pin passing through the core and having a contact point at its inner end, the outer end of 100 the pin being screw-threaded, and a binding nut on said pin, whereby a conducting wire may be connected thereto.

6. A spark plug comprising a plug base having a screw threaded neck, an electrode 105 attached to said neck and projecting beneath the base and having a contact point, an exteriorly threaded bushing engaging with the outer end of the base, a core of insulating material supported within the bushing and having a longitudinal passage extending through its center, an electrode pin passing through the passage of the core and having a contact point at its inner end, said pin being rotatable to provide means 115 whereby the extremity of the pin may have frictional engagement with the opposed contact point to clean said points, the outer end of the pin being screw threaded, and a binding nut on said pin whereby a conduct- 120 ing wire may be connected thereto.

7. A spark plug comprising a plug base, screw-threaded on its exterior, a bushing having screw-threaded engagement with the plug base, an electrode carried upon the inner end of the plug base, a core of insulating material carried by and longitudinally movable with the bushing, said core having a passage extending longitudinally through its center, the passage at its inner end being 125 130

enlarged, an electrode pin rotatably mounted in said passage, the lower end of the pin projecting below the core, the upper end of the pin being formed with screw threads, 5 and a binding nut engaging said screw threads.

8. A spark plug comprising a plug base having screw threads on its interior, a bushing having screw-threaded engagement with 10 the plug base, an electrode carried upon the inner end of the plug base, a core of insulating material extending through the bushing, said core being provided with opposed shoulders engaging opposite ends of the 15 bushing and said core having a passage ex-

tending longitudinally through its center, a threaded sleeve mounted within the core, a threaded electrode pin passing through the sleeve and engaging therewith, a lock nut on the pin, a binding nut thereon, and a 20 handle on the pin, whereby it may be rotated.

In testimony whereof we affix our signatures in presence of two witnesses.
